UNITED STATES PATENT OFFICE.

JOHN S. JUDGE, OF PETERBOROUGH, CANADA.

DESIGN FOR A VAPORIZER.

SPECIFICATION forming part of Design No. 25,509, dated May 19, 1896.

Application filed March 19, 1896. Serial No. 583,981. Term of patent 14 years.

To all whom it may concern:

Be it known that I, JOHN S. JUDGE, of Peterborough, in the Province of Ontario and Dominion of Canada, have invented and produced a new and original Design for a Vaporizer, of which the following is a full, clear, and exact description.

Reference is to be had to the accompanying drawings, forming a part of this specification, in which similar characters of reference indicate corresponding parts in both the figures.

Figure 1 is a perspective view of a vaporizer embodying my new design, and Fig. 2 is a cross-sectional view on line 2-2 of Fig. 1.

15 The leading feature of my design resides in

the tapering body having longitudinal corrugations therein, as shown, and having a rounding lower end.

Another feature of the design is the plain upper end of the body capped by a convex top with a curved elongated member departing from the center of the said top.

I claim—

The design for a vaporizer herein shown and described.

JOHN S. JUDGE.
